UNITED STATES PATENT OFFICE

JOSEF JANNEK AND OTTO GÖHRE, OF LUDWIGSHAFEN-ON-THE-RHINE, GERMANY, AS
SIGNORS TO I. G. FARBENINDUSTRIE AKTIENGESELLSCHAFT, OF FRANKFORT-ON-
THE-MAIN, GERMANY, A CORPORATION OF GERMANY

RECOVERY OF SOLUBLE PRODUCTS FROM SOLID CARBONIZABLE SUBSTANCES

No Drawing. Application filed March 15, 1928, Serial No. 262,041, and in Germany March 18, 1927.

This invention relates to the production of soluble products from carbonizable substances. By "soluble products" wherever this term is employed in the present application, are understood those products present in carbonizable substances or which are formed therein by heat treatment, which when isolated therefrom are either semi-solid or solid and are wholly or in part fusible and as a rule have a blackish color, and which are soluble in liquid organic solvents. The said products have a content in hydrogen which is about twice that of the carbonizable substances from which they have been extracted and they only contain about half the amount of oxygen.

It has already been proposed to improve the yield of soluble products obtained by extraction from coal with distillable liquid organic solvents either by heating the coal, under pressure, in the presence or absence of a distillable liquid organic solvent, and then effecting the extraction of the said soluble products by lixiviating with a larger amount of the said solvent, or, by heating the coal by itself without pressure, and then extracting as aforesaid, or, by heating under pressure with a distillable liquid organic solvent, after preheating without pressure, and then extracting. According to all known means, however, the increased yield, if any, is not very considerable.

We have now found that an unexpectedly high yield of the said soluble products may be obtained by extraction from carbonizable substances such as coal, or like carbonaceous materials, with distillable liquid organic solvents, if the said carbonizable substances are first heated by themselves in a closed vessel under pressure, and are then treated by extraction with an adequate amount of one of the said solvents, also in a closed vessel, at an elevated temperature and under pressure but the conditions of working must be so chosen in both stages of the process, when gases or vapours capable of reacting with the materials under treatment are employed, that no substantial reaction with the said gases takes place. It should be understood that the expression "carbonizable substances"

when employed in connection with the present invention does not include brown coal containing considerable amounts of moisture. In both stages the pressure is spontaneously set up by the heating, and it may be increased by the addition of non-oxidizing gases or vapors, which are equivalents for the purposes of the present invention and which under the conditions of working do not react to a substantial extent with the carbonizable matter such as nitrogen, carbon monoxid, hydrogen, steam and the like, or mixtures thereof. The pressure to be preferably employed is over 2 atmospheres but it may attain from 20 to 100 atmospheres or more. In the preheating treatment of the coal it is preferable to employ temperatures over 100° C. and up to 600° C. Prolonged heating, which may extend to several hours, may be advantageous. The conditions of working, as for example in respect of pressure, temperature, duration of heating, amount and kind of solvent, in order to obtain a maximum yield of soluble products in any given instance, must be adapted to suit the type of coal and solvent. When preheating brown-coal for example, temperatures between 200° and 400° C. are suitable. When preheating the coal, it is preferable to employ temperatures and pressures which do not cause the coal to cake. After heating under pressure, the coal may have a considerably modified appearance, but it is nevertheless substantially still in a firm condition. The coal is then, preferably while still hot, treated with a solvent, or mixture of solvents, in a closed vessel and at an elevated temperature, additional pressures being applied as required, the mass being preferably kept in motion or stirred. It may sometimes be advantageous to extract twice, or a greater number of times, with the same solvent, or different solvents. Suitable solvents according to the present invention comprise, for example, hydrocarbons such as benzene and its derivatives, hydrogenated naphthalenes, alcohols, ketones, petroleum, mineral oils, tar oils and the like. Cyclic alcohols and ketones, such as cyclohexanol and cyclo-

hexanone, and the like may be mentioned as being particularly suitable.

The process herein described may be applied to coals, or carbonaceous or carbonizable substances of any kind as for example brown-coal, peat, humus coal, pit coal, wood, oil shale, carbonaceous shale and the like.

The following examples will further illustrate the nature of the said invention, but the invention is not limited thereto.

Example 1

A pressure-tight vessel is about half filled with dry brown coal (lignite). After 15 placing the air from the said vessel by means of nitrogen the material to be treated is heated to a temperature of about 300° C. whereby a pressure of about 150 atmospheres or more is set up. If desired a non-oxidizing 20 gas, such for example as nitrogen may be pressed into the said pressure-tight vessel prior to heating. In this case the pressure attained by heating is still higher. After heating for about 10 hours, the vessel is allowed to cool down for about 3 to 6 hours, 25 depending on the amount of the charge and, after releasing the pressure, about double the amount of distillable liquid organic solvent, such as benzene, is introduced to the pre-treated lignite. After closing down the vessel, the materials are again heated to a temperature of about 300° C., if desired, after 30 pressing in, for example 30 atmospheres of nitrogen. After heating for about 4 to 10 hours the vessel is again allowed to cool 35 down for about 3 to 6 hours and is relieved of pressure and is emptied. After filtering, centrifuging or similarly treating the product thus obtained, whereby the solid materials are separated from the liquid constituents, the solid residue is washed with further 40 quantities of fresh solvent or is further subjected to extraction by means of a solvent without the application of pressure. The solvent may be removed from the products 45 which have been extracted from the lignite by means of simple distillation or vacuum distillation or steam distillation.

Example 2

50 Dry brown-coal from the mid-German field, from which 1.7 per cent of bitumen can be extracted with benzene in a Soxhlet apparatus, is heated at 300° C. for 10 hours in an autoclave, during which treatment a pressure 55 of about 100 atmospheres is produced, and a loss in weight of about 14 per cent occurs. The material which has been thus pretreated is subjected to extraction with benzene for 10 hours at 300° C. in a closed vessel a pressure 60 of about 100 atmospheres being thus set up. A yield of over 60 per cent of soluble products with reference to the coal substance treated, is thus obtained.

The soluble products obtained according 65 to the foregoing example may be subjected

either alone or in association with the solvent or the undissolved residue to further treatment, such as a cracking process in the presence of activated aluminium and hydrogen chlorid, or to destructive hydrogenation. 70 After separation of the insoluble portion and the solvent, the said products may also be separated, by the aid of suitable solvents, into resins, waxes and other substances, as for example, by first treating the product 75 with ether to extract the resinous constituents, and then extracting the wax-like constituents from the residue by treating with hexane or the like. The constituents may afterwards be used as such or subjected to 80 further treatment.

What we claim is:

1. A process for the production of products which are soluble in organic liquids from solid carbonizable substances which comprises heating the said carbonizable substances under a pressure of at least 2 atmospheres at a temperature of at least 100° C. but below the point at which the said carbonizable substances cake, and then treating the products thus obtained by extraction with an adequate amount of a liquid distillable organic solvent at an elevated temperature and under a pressure of more than 2 atmospheres, the conditions of working in both 95 stages of the process being so chosen that, when gases or vapours capable of reacting with the materials under treatment are employed, no substantial reaction with the said gases takes place.

2. A process for the production of products which are soluble in organic liquids from solid carbonizable substances which comprises heating the said carbonizable substances to temperatures of between 100° and 600° C. under a pressure of more than 2 atmospheres and then treating the products, while still hot, by extraction with an adequate amount of a distillable liquid organic solvent at a pressure of more than 2 atmospheres, the conditions of working being so chosen in both stages of the process, when gases or vapours capable of reacting with the materials under treatment are employed, that no substantial reaction with the said gases 110 takes place.

3. A process for the production of products which are soluble in organic liquids from solid carbonizable substances which comprises heating the said carbonizable substances together with a gas which under the conditions of working does not react to a substantial extent with the carbonizable matter to temperatures between 100° and 600° C. under a pressure of more than 2 atmospheres and then treating the product, while still hot, by extraction with an adequate amount of a distillable liquid organic solvent at a pressure of more than 2 atmospheres, the conditions of working being so chosen in the said 115

extraction treatment, when gases or vapours capable of reacting with the materials under treatment are employed, that no substantial reaction with the said gases takes place.

4. A process for the production of products which are soluble in organic liquids from solid carbonizable substances which comprises heating the said carbonizable substances to temperatures of between 100° and 600° C. under a pressure of more than 2 atmospheres under such conditions that, when gases or vapours capable of reacting with the materials under treatment are employed, no substantial reaction with the said gases takes place, and then treating the product, while still hot, by extraction with a distillable liquid organic solvent and a gas which under the conditions of working does not react with the carbonizable material at a pressure of more than 2 atmospheres.

5. A process for the production of products which are soluble in organic liquids from solid carbonizable substances which comprises heating the said carbonizable substances, together with a gas, which, under the conditions of working, does not react to a substantial extent with the carbonizable material, to temperatures of between 100° and 600° C. under a pressure of more than 2 atmospheres and then treating the product, while still hot, by extraction with an adequate amount of a distillable liquid organic solvent together with a gas which under the conditions of working does not react to a substantial extent with a carbonizable material, at a pressure of more than 2 atmospheres.

6. A process for the production of products which are soluble in organic liquids from solid carbonizable substances which comprises heating the said carbonizable substances under a pressure of more than 2 atmospheres and at a temperature of between 100° and 600° C. and then treating the product by extraction with an adequate amount of a distillable liquid organic solvent at an elevated temperature and at a pressure of more than 2 atmospheres, the conditions of working being so chosen in both stages of the process, when gases or vapours capable of reacting with the materials under treatment are employed, that no substantial reaction with the said gases takes place, and subjecting the resulting products to a cracking operation.

7. A process for the production of products which are soluble in organic liquids from solid carbonizable substances which comprises heating dry brown coal to temperatures of between 200° and 400° C. under a pressure of more than 2 atmospheres which is not so high as to cause the coal to cake, and then treating the product, while still hot, by extraction with an adequate amount of a distillable liquid organic solvent at a pressure of more than 2 atmospheres, the conditions of working being so chosen in both

stages of the process, when gases or vapours capable of reacting with the materials under treatment are employed, that no substantial reaction with the said gases takes place.

8. A process for the production of products which are soluble in organic liquids from solid carbonizable substances which comprises heating dry brown coal to about 300° C. for 10 hours at a pressure of about 100 atmospheres and then subjecting the product to extraction by heating with an adequate amount of benzene for further 10 hours at about 300° C. under a pressure of more than 2 atmospheres, the conditions of working being so chosen in both stages of the process that, when gases or vapours capable of reacting with the materials under treatment are employed, no substantial reaction with the said gases takes place.

9. A process for the production of products which are soluble in organic liquids from solid carbonizable substances which comprises heating the said carbonizable substances under pressure at a temperature of at least 100° C. and below the point at which the said carbonizable substances cake and then treating the product thus obtained by extraction with at least twice the amount of a liquid distillable organic solvent at an elevated temperature and at a pressure of more than 2 atmospheres, the conditions of working being so chosen in both stages of the process that, when gases or vapours capable of reacting with the materials under treatment are employed, no substantial reaction with the said gases takes place.

In testimony whereof we have hereunto set our hands.
